GAMEBOARD

Curtis Williamson, 20903 Doepfer, Warren, Mich., and Donald Hall, 2651 Lycaste, Detroit, Mich.

Filed Sept. 7, 1960, Ser. No. 62,049

Term of patent 14 years

(Cl. D34—5)

The single figure is a top plan view of a gameboard of conventional thickness showing our new design. The dominant features of our design reside in the portions shown in full lines.

We claim:

The ornamental design for a gameboard, as shown and described.
